(57) CLAIM

The ornamental design for a jar for cosmetics as shown and described.

DESCRIPTION

FIG. 1 is a perspective view of a jar for cosmetics showing my new design;

FIG. 2 is a front view thereof;

FIG. 3 is a top plan view thereof;

FIG. 4 is a bottom plan view thereof;

FIG. 5 is a right side view thereof, a left side view being symmetrical to the right side view;

FIG. 6 is a cross-sectional view thereof along the line 6-6 in FIG. 2;

FIG. 7 is a front view of a jar for cosmetics base, wherein the lid is removed to show aspects not visible when combined;

FIG. 8 is a top plan view thereof; and,

FIG. 9 is a right side view thereof.

The broken lines depict portions of the jar for cosmetics that form no part of claimed design.

1 Claim, 5 Drawing Sheets
